CAN DRYING MACHINE

Charles J. Kolper and Frank Drega, Baltimore,
Md., assignors to Gibbs & Company, Incorporated,
Baltimore, Md., a corporation of Maryland

Application July 22, 1947, Serial No. 762,554

8 Claims. (Cl. 34—95)

1

This invention relates to a can drying machine. In the canning industry, it is the usual practice, after the cans have been filled with vegetables, fruits, or other food products and then processed, to subject the cans to a bath or stream of cool water for the purpose of washing and partially cooling the same preparatory to the application of identifying labels or wrappers. In so doing, the cans retain varying amounts of water and unless the same is removed it is not possible to make the labels adhere to the cans.

Various drying structures have heretofore been developed or suggested, but they have failed to provide an effective removal of this water from both the cylindrical and end surfaces of the cans in an automatic manner and in keeping with the usual continuous conveying movement of the cans from the washing and cooling apparatus to the label applying machines.

It is a primary object of this invention to provide a drying machine which may be positioned between a can washer and a label applying machine, and which is effective in absorbing the moisture from both the cylindrical and end surfaces of the cans in rapid succession as the same are conveyed from the washer to the label applying machine.

It has been found that water, after the filled cans have been processed, washed and cooled in any of the well known ways, adheres to the cans, for the most part directly beneath the beads or flanges on the ends of the cans, and which, if not thoroughly removed, will seriously interfere with the labeling or wrapping operation.

It is accordingly a further object of the invention to provide a can drying machine which is effective to thoroughly wipe the ends of the cans and remove all water which may have accumulated beneath the beads or flanges on the ends of the cans.

A still further object of the invention is the provision of a can drying machine having provision for the delivery of cans at successively spaced intervals within the range of a traveling water absorbent belt which dries the cylindrical surfaces of the cans and advances same to a station having provision for the drying of the ends of the cans, the cans at such station being retained against advancing movement until released by the successive cans advanced by the belt as same are delivered thereto.

A still further object of the invention is the provision of a can drying machine which is relatively simple in construction, highly efficient in operation, and which embodies various adjustable

features whereby rendering the machine capable of operation on various size cans with a minimum of change in the structural elements of the machine.

Other objects and advantages of the invention will become apparent in the course of the following detailed description, taken in connection with the accompanying drawings, wherein:

Figure 1 is a side elevational view of the improved machine in accordance with a preferred structural embodiment thereof, the water-collecting pan being shown in longitudinal vertical section.

Figure 2 is a top plan view of the machine, the water pan not being shown and other elements being shown in part and in dotted lines.

Figure 3 is a side elevational view, on an enlarged scale, of the can stop and releasing means at the can end drying station.

Figure 4 is an axial sectional view of one of the can end drying structures.

Figure 5 is a sectional view at right angles to the axis of the can end drying structure of Figure 4.

Figure 6 is an enlarged fragmental edge view of the can drying and advancing belt.

Referring now in detail to the drawings, the machine includes a suitable frame which may be of various constructions but which is illustrated in a suitable form as embodying a pair of vertically disposed and laterally spaced front uprights 10 and a pair of similar rear uprights 11. The uprights are arranged in rectangular position as viewed from above and their lower ends are seated on the bottom 12 of a water-collecting pan 13. A pair of bars 14 are suitably secured to the upper ends of the uprights 10 and 11 and are disposed horizontally and in parallel relation above the pan 13.

A bar 15 of L-section extends transversely of and between the front uprights 10 and the rear uprights 11 and the ends of such bars are connected to the uprights for vertical adjustment in slots 16 in the latter.

A pair of can-engaging tracks or rails 17 are supported on the bars 15 for lateral adjustment thereon, as indicated at 18 in Figure 2. The rails 17 are interrupted at a can-end drying station S, and the adjacent spaced ends of each rail at such point of interruption are connected by a plate 19. Each plate 19 pivotally supports a pair of rollers 20, 21 in substantial alignment with the rails 17, and the roller 20 is provided with a flange 21 for engaging the adjacent end of the can.

The circumference of roller 20 is substantially

tangent to the can-engaging surface of the rail 17, while roller 21 is disposed at a slightly greater elevation, and the rail 17 is provided with a plate 22 having a rounded rear end 23, for a purpose later to appear.

A belt 24 is provided for advancing the cans toward the can-end drying station S as well as for drying the cylindrical surfaces of the cans, and for this purpose the belt is preferably constructed of a band of rubber 25 (Figure 6) to which is suitably secured a water-absorbing chamois band 26. The belt is disposed above the rails 17, and is trained about a pair of rollers 27 and 28 adjacent the front and rear ends of the machine, respectively, and the front roller 27 is carried by a shaft 29 rotatably supported in the bars 14, while the rear roller 28 is carried by a shaft 30 rotatably supported at each end in a block 31 adjustable lengthwise of the bars by a screw 32 having swivel connection with the block. By this construction, the roller 28 may be moved rearwardly to tension the belt 24.

A gear wheel 33 is secured to shaft 29 outwardly of one of the bars 14, which gear wheel is in mesh with and driven by a smaller gear wheel 34 fixed to a shaft 35 extending transversely over the bars 14 and which is rotatably journaled in plates 36 suitably secured to the inner faces of said bars.

The shaft 35 has fixed thereto a pulley 37 which is driven by a belt 38 from a pulley 39 on a motor 40 which is disposed on a platform 41 supported above the bars 14, as by plates 42. The shaft 35 has fixed to its end opposite pulley 37 a pulley 43 which is drivingly connected to a pulley 44 by a crossed belt 45, whereby pulleys 43 and 44 rotate in opposite directions.

The pulley 44 is fixed to one end of a shaft 46 which extends transversely above the bars 14 and is rotatably journaled in bearing plates 47 suitably secured to the bars 14.

The shaft 46 fixedly supports a bevel gear 48 adjacent each end thereof. The gears 48 each mesh with a bevel gear 49 secured to an end of a shaft 50 extending above each bar 14. The shafts 50 are each rotatably supported in a pair of brackets 51 secured to the adjacent bar 14 and which bars are inwardly recessed as at 52 between the brackets.

A shaft bearing member 53 is disposed opposite each of the recesses 52 and includes a pair of ears 54 swingingly supported on the adjacent shaft 50. A vertically disposed shaft 55 is rotatably supported in the bearing member 53 and fixedly supports a bevel gear 56 at its upper end which is in meshing engagement with a bevel gear 57 fixed to shaft 50.

Thus, it will be seen that shaft 55 is rotatable by gears 48, 49, 56 and 57 while it is also free for swinging movement about the axis of shaft 50.

The bearing member 53 together with its journaled shaft 55 is yieldably urged toward the recess 52 by means of a pair of springs 60, one at each end of a plate 61 and with the corresponding ends of the springs connected with the plate. The opposite ends of the springs are connected to bar 14 and the plate is adjustably connected with member 53 by means of a screw 62 for adjusting the tension of the springs. An adjustable stop 63 is provided for each member 53 to limit inward movement thereof.

The shafts 55 extend downwardly into proximity to the can end drying station S, and each such shaft is provided with a can end wiping structure which, as is more clearly shown in

Figures 4 and 5, comprises a plurality of superposed chamois discs 64. These discs, while being generally circular, may be somewhat irregular as indicated in Figure 5, and the plurality of discs 5 are threaded onto the lower end of the shaft 55 and clamped between a pair of washers 65 and cooperating nuts 66. The discs need not be tightly clamped. At any rate, they are substantially loose adjacent their peripheries and in fact dangle away from each other, as indicated in Figure 4.

The compression of the discs can readily be varied by the washers and nuts 65, 66, and their position axially of the shaft changed. Furthermore, the depth of the package of discs can be varied, but such is preferably slightly greater than the radius of a can end to be dried.

The lower reach of the belt is downwardly tensioned by means of a plurality of leaf springs 67 whose free ends engage the belt from within and whose opposite ends are suitably secured to rods 68 extending through laterally aligned apertures in bars 14, and the rods at corresponding ends thereof are threaded and nuts 69 engage such threaded ends and normally frictionally engage one of the bars 14. The rods 68 are slotted as at 70 whereby they may be turned as by a screw driver when the nuts 69 are released, and in so doing the tension of the springs may be adjusted.

The filled and processed cans C to be dried are fed into the forward end of the machine preferably by a suitable conveyor which delivers the cans in succession onto the forward ends of the track rails 17, and upon engagement of the cans by the lower reach of the belt 24 they are advanced to the end drying station S while the outer chamois layer 26 of the belt absorbs the water from the cylindrical surfaces of the cans.

In order that the ends of the cans be thoroughly dried it is necessary that the successive cans be retained at the drying station for a relatively short interval of time, and accordingly stop means are provided for arresting advancing movement of the successive cans when they reach the station S. Such stop means comprises an elongated bar 71 disposed between the rails 17 and pivotally connected thereto as at 72 adjacent one end of the bar. The opposite end of the bar is of arcuate form and extends upwardly between the two pairs of rollers 20, 21, as is clearly shown in Figure 3 at 73, which provides a can stop. The arcuate stop 73 is yieldably urged upwardly into operative position by means of a spring 74 adjustably connected to the bar 71 as at 75 and adjustably connected at 76 to a clip 77 supported by a member 78 whose opposite ends are suitably supported by the uprights 10 and 11. Upward movement of the stop 73 is limited by a chain 79 whose upper end is connected to the bar 71 and whose lower end is adjustably connected as at 80 to the member 78.

A can C is shown in each of Figures 1 and 3 resting on the rollers 20, 21 with the stop 73 disposed adjacent the cylindrical surface of the can 65 rearwardly thereof. In this position, the belt 24 will cause the can C to rotate about its axis and on the rollers 20, 21 and the opposed chamois structures including the discs 64 will be rotating, whereby the combined rotation of the can about its horizontal axis and the rotation of the chamois discs 64 about vertical axes will effect thorough drying of the can ends without the possibility of water being retained beneath the end beads on the cans.

Since it is desirable that the cans be retarded

at the station S against forward advancing movement, it is necessary that the successive cans be fed into engagement with the belt in spaced relation, and for this reason the machine includes can-spacing means. The can-spacing means comprises a pair of rubber or rubber-faced rolls 82 fixed to a shaft 83 which is rotatably journaled in arms 84 adjacent their free ends, the opposite ends of the arms being pivotally connected to bars 14 as at 85. The arms 84 are interconnected by a strut 86, thereby providing a rigid frame. This frame is yieldably urged downwardly by means of a coil spring 87, and an adjustable stop 88 limits such downward movement. The shaft 83 is provided with a sprocket wheel 89 which is drivingly connected by a sprocket chain 90 with a smaller sprocket wheel 91 fixed to the end of shaft 29.

As a can C is fed between the rails 17 and rolls 82 it will be advanced relatively slowly as compared with the movement of belt 24, and since the period of time in which a can is engaged with the rolls 82 can be determined through vertical adjustment of the rolls by means of the stop 88, the spacing of the cans as they engage the belt 24 can be readily varied.

The stop bar 71 is provided with a stop release member 92 which at one end is connected to the bar and which at its opposite end curved upwardly. Thus, when a successive can C' is advanced by the belt 24 from the spacing rolls 82, it engages the upwardly curved releasing member, as in Figure 3, and forces the stop 73 downwardly and the advancing can C' engages the dried can C and pushes it forwardly as at C'', the can C'' riding down over the plate 22 to avoid dropping of the can when riding off the roller 21.

A wringer roll 93 is provided and the opposite ends thereof are rotatably journaled in blocks 94 between which and the heads of adjusting screws 95 are disposed coil springs 96. The wringer roll engages the belt 24 opposite roller 27 and is in adjustable yieldable engagement therewith.

It will be appreciated from the foregoing disclosure that a can drying machine is provided in accordance with this invention which, while being of relatively simple and rugged construction, is adapted to effectively dry both the cylindrical and end surfaces of cans with a minimum of expenditure of time and effort on the part of an operator.

In operation, the cans to be dried will be presented to the can-spacing means including the rolls 82 by a conveyor, by which the cans are moved from a combined washing and cooling device. The cans will be successively engaged by the rolls 82 which will be adjusted in a manner to deliver the cans in spaced successive relation to the action of the belt 24. The cans, upon being engaged by the belt, will roll on rolls or tracks 17 and thereby be advanced toward the can end drying station S. Furthermore, the entire cylindrical areas of the cans will be engaged by the chamois band included in the belt construction, and such areas or surfaces will be thoroughly dried.

The cans upon reaching the end drying station will be retained by the stop means and will be rotated on their axes for operation of the rotatable chamois discs on the ends thereof, the cans being rotated on horizontal axes and the chamois discs rotated on vertical axes. The chamois discs will be yieldably retained in pressure contact with the can ends, whereby an effective wiping action will be attained.

The succeeding spaced cans being advanced by the belt will successively release the stop means and, by contact with the cans at the drying station, push same therefrom for drying action on the following cans being advanced by the belt. Since the lower reach of the belt 24 is vertically yieldable and the can end wiping structures are laterally yieldable, cans of slightly different diameters and lengths may be dried without any adjustment of the machine.

For use with cans of substantially different dimensions, the rails 17 may be adjusted both vertically and laterally and a belt 24 of a different width applied in the machine.

While we have disclosed our invention in accordance with a single specific embodiment thereof, such is to be considered as illustrative only, and not restrictive, the scope of the invention being defined in the following claims.

What we claim and desire to secure by U. S. Letters Patent is:

1. A can drying machine comprising an elongated frame including a pair of parallel laterally spaced bars, a pair of tracks engageable by the cylindrical end portions of cans and supported by said frame substantially below said bars, a pair of rollers carried by shafts rotatably supported by said bars above said tracks, a belt of a width substantially equal to the lateral spacing of said tracks trained around said rollers, with the lower reach of said belt operative to engage the cylindrical surfaces of cans and advance the cans along said tracks, a pair of substantially vertically disposed shafts, each rotatably supported by one of said bars adjacent each track, said last shafts being directly opposed laterally of the tracks and depending from said bars, a can-end wiping member carried by the lower end of each of said last named shafts, and power and drive means for rotating said roller shafts and said vertical shafts.

2. A can drying machine according to claim 1, wherein said last named shafts are supported for swinging movement laterally of said rails, and adjustable yieldable means for urging said shafts toward each other whereby said wiping members will effectively engage the opposite ends of the cans.

3. A can drying machine according to claim 1, together with stop means operative to retain cans in a position to be dried by said wiping members and against advancement by said belt for a predetermined interval of time, and releasing means associated with said stop means and operative by a next succeeding can to release the stop from the next preceding can.

4. A can drying machine according to claim 1, wherein said belt comprises an outer band of water-absorbing material, and a wringer roller supported by said frame and yieldably engaged with said belt in opposition to one of said rollers.

5. A can drying machine according to claim 1, together with vertically adjustable can-engaging rolls disposed in advance of said belt and operative to engage a portion of the circumference of successive cans for spacing and delivering same to said belt.

6. A can drying machine according to claim 1, wherein said wiping member comprises a plurality of superposed water absorbing disc like members through which said vertical shaft extends, and means carried by said shaft and operative to adjustably compress said members as well as to vary the position thereof lengthwise of the shaft.

7. A can drying machine according to claim 1,

7
wherein said frame is supported in a water-collecting pan with said tracks disposed above the top of the pan.

8. A can drying machine according to claim 1, together with a plurality of leaf springs disposed between the upper and lower reaches of the belt and having lower free ends engageable with the inner face of said lower reach to downwardly tension same for firm gripping contact with cans advanced thereby, the upper ends of the springs being secured in rods extending transversely through the frame, nuts on corresponding threaded ends of the rods for binding same against rotation in the frame, and slots in said ends of the rods for receiving a tool for rotation of the rods to adjust the springs upon release of the nuts.
